UNITED STATES PATENT OFFICE.

FRED KALE, OF WINTERSET, IOWA.

GATE-OPERATING DEVICE.

1,402,512.

Specification of Letters Patent. Patented Jan. 3, 1922.

Application filed June 8, 1920. Serial No. 387,434.

To all whom it may concern:

Be it known that I, FRED KALE, a citizen of the United States, and a resident of Winterset, in the county of Madison and State of Iowa, have invented a certain new and useful Gate-Operating Device, of which the following is a specification.

My invention relates to that class of gate operating device in which the wheels of a vehicle approaching the gate engage the crank device located in the road way, and upon the operating of said crank device, a pull is exerted on a cable connected to the gate, whereby the gate may be swung open in the direction away from the approaching vehicle.

The object of my invention is to provide a device of this character, of simple, durable and inexpensive construction which may be used in the nature of an attachment to apply to gates of the ordinary sort, and in which the first impact of the vehicle wheel approaching the gate will be utilized partly in operating the gate unlatching device and partly in opening the gate, and the impact of the second or hind wheel of the vehicle will be utilized in completing the opening movement of the gate, thereby avoiding undue shock and strain to the gate operating mechanism, such as is occasioned by devices of this general character in which the entire operating of the gate unlatching and opening is done upon the first impact of the front wheels of the vehicle.

A further object is to provide a device of this kind in which one spring only is utilized for the purpose of maintaining all of the cables under proper tension and in permitting the first impact of the vehicle wheels to exert its force in unlatching the gate and before any considerable tension is applied to the gate tending to swing it open.

With these and other objects in view, my invention consists in the construction, arrangement and combination of the various parts of the device, whereby the objects contemplated are attained, as hereinafter more fully set forth, pointed out in my claim, and illustrated in the accompanying drawings, in which:

Figure 1 shows a top or plan view of my gate operating device, as installed on a gate.

Figure 2 shows a side elevation of the gate with the drum mechanism mounted thereon.

Figure 3 shows enlarged detail view,

partly in section illustrating the drum attached to the lower part of the gate in line with its pivotal center, to illustrate the arrangement of the cables and springs thereon. 60

Figure 4 shows a sectional view through the tread devices with a vehicle wheel about to engage the tread devices.

In the accompanying drawings, I have used the reference numerals 10 and 11 to indicate posts for supporting the gate 12. Hinges 13 are provided on the gate and are adapted to be received in the post 10, whereby the gate may swing to various positions. 70

A latch device 14, which comprises a member 15, is fixed to the post 11, while the member 16 of the latch device 14 is pivoted to the gate 12.

Supported on the gate substantially below 75 the hinges 13 is the drum 17, which is held in position by the U-bolts 18.

Disposed at either side of the gate 12 are the operating mechanisms A and B. The operating mechanisms A and B each comprise tread engaging wheels or paddles 19, which are rotatably mounted on a shaft 20. The shaft 20 is journaled in a casing 21, which is slightly sunk into the ground. The casing 21 may be of concrete or steel as 85 desired.

Fixed adjacent to the paddle wheels of the tread device 19 is the drum 22. The drums 22 are adapted to rotate on the shaft 20.

Connecting the drums 22 of the operating 90 mechanisms A and B and the drum 17 is the cable 23. The cable 23 has one of its ends fixed to the drum 17. The other end of the cable 23 is fixed to a spring 24; the opposite end of the spring 24 is fixed to the drum 17 95 at 25. The end of the cable 23, which is fixed to the drum, is held in position by means of the staple 26 shown in Figure 3 of the drawings.

The cable 23 is lapped around the drum 17 100 and the drums 22 substantially as illustrated in Figures 1 and 3 of the drawings.

Mounted near the upper portion of the gate is the bearing 27, which is provided with a small pulley wheel 28, shown in dotted 105 lines in Figure 2.

A cable 29 is received around the pulley wheel 28 and has one end fixed to the member 16 of the latch device 14; while its free end is fixed to the spring 24 at the point 110 where the spring 24 is fixed to the cable 23.

In the practical operation of my device, a

vehicle wheel, indicated by the reference numeral 30, strikes one of the paddle wheels 19 as the tread device and causes the tread device to be rotated substantially a third of 5 a revolution.

The rotation of the tread device or paddle wheel 19 causes the drums 22 of the operating mechanisms A and B to rotate, causing the cable 23, which is fixed to the drum 17 10 to move the drum 17.

When the vehicle wheel 30 first strikes the tread engaging devices, it will cause the cable to be tightened by pulling the spring 24. But as soon as the spring 24 has reached 15 its limit of movement, the further movement of the cables 23 will cause the gate to be opened or closed.

The first movement of the cable 23, which causes the spring to be extended, will cause 20 the cable 29 to be tightened, which in turn will lift the latch member 16 out of the coacting member 15, thus releasing the latch device and permitting the gate to be swung to open position.

25 For example, if the operating mechanism A were passed over by a vehicle wheel, the tightening of the cable would first cause the latch device 14 to be released, and as soon as it were released, the gate would be free to 30 swing to open position.

After the vehicle has passed through the gate, it then passes over the operating mechanism B, which is similar to the mechanism A and causes the cables to be moved in the 35 opposite direction, which will cause the gate to be closed.

The member 16 of the latch device 14 will coact with the member 15 from its own accord due to its weight.

40 It will be understood that both the front and rear wheels of the vehicle pass over the operating mechanisms A and B, the front wheel causing the gate to merely swing open substantially one-eighth of a revolution, 45 while the rear wheel will complete the opening of the gate, which is substantially a quarter revolution.

It will be noted that the entire device is 50 of simple, durable and inexpensive construction, and may be used in the nature of an attachment to apply to a gate already erected. On account of my improved construction of having the drum secured to the gate below its hinged center, and by having a 55 spring fixed to the drum and also by having one end of the gate operating cable fixed to the drum and the other end to said spring, and also by having the gate latch cable fixed to the same spring, the following advantage-

60 ous results are attained: First, the construction is quite simple and inexpensive, and sec-

ond, no matter which one of the paddles 19 is engaged by the vehicle wheels, the first effect of the movement of the paddle will be to stretch the spring. The first part of this 65 spring stretching movement will result in releasing the latch before any considerable tension is applied in the direction tending to open the gate, so that the latch is easily raised. After that the remainder of the 70 paddle movement will be exerted in partially opening the gate and the second impact on the next paddle, by the rear wheel of the vehicle, will continue the gate opening movement so that the entire movement of the 75 gate will be relatively slow and uniform in proportion to the speed of the vehicle, thus relieving the gate operating device of undue shocks and strains.

Some changes may be made in the construction and arrangement of the parts of my improved gate operating device, without departing from the essential features and purposes of my invention, and it is my intention to cover by my claim any modified 80 forms of structure or use of mechanical equivalents, which may be reasonably included within its scope.

I claim as my invention:

A gate operating device comprising, in 90 combination, a gate, a latch, a drum secured to the gate below its pivotal point, a cable having one end fixed to the drum, a contractile coil spring fixed to the drum and having the other end of said cable attached to its 95 free end, a latch operating cable also fixed to the free end of said spring and attached to the latch, and two gate operating devices 100 designed to be mounted in a road way on opposite sides of the gate, each of said devices comprising a drum around which said cable is passed, and a series of paddles, each 105 capable of moving in a complete circle and so spaced apart that the front wheel of an approaching vehicle may engage a paddle and move it a part revolution, and the second or rear wheel of the vehicle will engage the succeeding paddle and move it another part 110 of a revolution, said parts being so arranged and combined that at the first impact of the wheel of the vehicle the said spring will be partly stretched out, and during the first part of this movement the latch will be opened, and then the spring will be brought under full tension and the gate will be 115 partly opened, and then upon the impact of the second wheel on the second paddle, the opening movement will be completed, for the purposes stated.

Des Moines, Iowa, May 11, 1920.

FRED KALE.
